UNITED STATES PATENT OFFICE.

THURE LARSSON, OF WORCESTER, MASSACHUSETTS.

HYDRAULIC VALVE.

Application filed March 10, 1923. Serial No. 624,202.

To all whom it may concern:

Be it known that I, THURE LARSSON, a citizen of the United States of America, residing at Worcester, in the county of Worcester and State of Massachusetts, have invented 5 certain new and useful Improvements in Hydraulic Valves, of which the following is a full, clear, and exact specification.

My invention relates to hydraulic valves 10 and more particularly to a three way piston valve mechanism for controlling the operation of a fluid motor.

One common type of mechanism for operating the plunger of an elevator comprises, 15 as shown in the patent to Reynolds, 314,720, March 31, 1885, a three way valve which serves to control the admission of fluid under pressure to the plunger cylinder and its discharge therefrom. This valve is moved 20 to predetermined positions by a piston contained in the valve casing, to which motive fluid is admitted by an auxiliary pilot valve under the control of the operator.

In such prior constructions, movement of 25 the valve is caused by the pressure of the incoming water supply, balanced pistons being employed to neutralize the back pressure of the fluid in the plunger cylinder. The speed of movement of the valve and hence the rate 30 at which fluid flows into the cylinder is regulated by an adjustable screw or valve which throttles down the size of the water passage, and such rate is fixed in accordance with 35 the preliminary adjustments made upon the mechanism.

The weight of the plunger is nearly balanced by counterweights so that the water pressure is required merely to do the work 40 of lifting the unbalanced portion of the load and moving it at the required speed. In operation, it is found that when the supply of water under pressure is suddenly shut off from the plunger cylinder, the plunger tends 45 to keep on moving because of the inertia of the heavy mass. Consequently the plunger may leave the surface of the water momentarily and then fall back on it with a shock which causes discomfort to the passengers in 50 the elevator car. Such sudden stoppage of the water flow also puts a severe strain on 55 the valves and casing, hence it is desirable that mechanism be employed which automatically stops the motor gradually and that it not be necessary to depend upon the skill of the operator for this purpose.

It is accordingly the prime object of my

invention to provide a valve mechanism which will so control the application of fluid pressure to a motor that the motor may be gradually stopped in its movement and 60 shocks incident to valve operation eliminated.

A further object is to provide a motor valve mechanism in which the motor back pressure is employed to control the rate of 65 valve movement automatically depending on the inertia of the load being moved.

It is a still further object to provide a three way piston valve for a hydraulic motor in which the inlet valve may be closed 70 and the outlet valve opened only by the back pressure from the motor port.

With these and further objects as will be apparent in the following disclosure, my invention resides in the combination of parts 75 described in the following specification and set forth in the appended claims.

In accordance with my invention, I propose to operate a motor, such as a reciprocatory plunger mechanism, by means of a 80 three way piston valve device in which the pressure of the inlet motive fluid on the piston sets is normally balanced and the back pressure thereon from the fluid in the motor is unbalanced, whereby the rate of 85 valve movement may be governed by the inertia of the load. To this end I preferably employ differential pistons on opposite sides of the port to the motor and balanced pistons on opposite sides of the port through which 90 the fluid under pressure enters and so arrange these parts that the fluid pressure in the motor port controls the valve movement.

Referring particularly to the drawing, the figure is a vertical section showing somewhat diagrammatically one embodiment of 95 my invention, as applied to the operation of a plunger elevator, although it will be clear that this invention is broadly applicable to various types of hydraulic motors 100 and particularly to those machines which comprise a reciprocatory piston or plunger. As there shown, the motor for moving an elevator car comprises a plunger 10 mounted to reciprocate in a cylinder 11 which is 105 closed at its lower end and has a suitable stuffing box 12 at the other end through which the piston slides. As is well known in the art, the weight of the plunger and the car or other load, illustrated diagrammatically by part 13, may be suitably counterbalanced so that the motor will be re-

quired to lift but the unbalanced excess of the weight. Fluid under pressure to raise the plunger is admitted to the cylinder 11 through a pipe 14 which also serves as an 5 exit for the fluid when the plunger descends.

As a simplified form of a three way valve capable of admitting motive fluid to the cylinder and of permitting its exhaust therefrom, I may provide a casing 15 which 10 has an inlet port 16 for fluid such as oil or water maintained under a hydraulic head, an exit port 17 and a motor port 18 which communicate with pipe 14. The ports 16 and 18 are arranged out of alignment on the 15 side of casing 15 so that a main valve 20 placed therebetween may be employed to control the flow of water to the motor cylinder. This valve 20 is mounted for reciprocation within a sleeve 21 which is suitably 20 fitted within the casing 15. In order that the pressure of the water in inlet port 16 may not move the main valve 20 I provide a piston 22 also sliding within the sleeve 21 which with the valve 20 forms a balanced piston set. The valve 20 itself serves 25 as a piston and owing to the fact that the pistons 20 and 22 are located on opposite sides of the inlet port, any pressure of the water therefrom will not move the balanced piston set in either direction.

These piston members are mounted centrally upon a rod 24 and fastened thereto by suitable means so that they may move in unison. The upper reduced end 25 of the 30 rod passes through the end wall 26 of the casing 15, and has a sliding fit therein through a stuffing box. This construction forms a piston chamber 27 between the piston 22 and the wall 26.

40 The rod 24 also extends downwardly below the piston valve 20 and carries on its lower end 29 a further piston valve 30 adapted to control the exit of water through the port 17. In order to provide a cylinder 45 for the piston 30, the sleeve 21 is extended as a reduced portion 32 within which piston 30 has a sliding fit. A shoulder 33 between the enlarged and reduced portions of the sleeve serves to limit the downward movement of the piston valve 20. Above this shoulder ports 34 are formed within the sleeve which open into an enlarged annular chamber 35 within the casing 15, which communicate with the port 18 and pipe 14 of the cylinder. Similarly, the space 35 communicates with the inside of the reduced sleeve 32 through ports 36 so that when the valve 30 is raised to its uppermost position water 50 may flow downwardly through port 18 and ports 36 to the exit port 17.

As will be readily apparent, the ports and pistons are so located and arranged that piston 22 remains always above the inlet opening 16. The valve 20 may be located as 55 shown in the drawing above the sleeve open-

ing 34 and therefore prevent the passage of water from port 16 through the valve or it may be lowered to the limiting position defined by shoulder 33 to permit water to flow to the cylinder. When valve 20 is in the 70 intermediate position illustrated, valve 30 similarly remains within the lower portion of the sleeve 32 below ports 36 and the two valves 20 and 30 thereby prevent water flowing in either direction through the pipe 75 14. By raising the valve 30 while valve 20 remains in a closed position water may be permitted to flow from the cylinder downwardly through the exit.

As a simplified form of motor mechanism 80 for actuating the valves, I may employ the construction shown in the drawing, whereby fluid under pressure may be admitted to the valve actuating cylinder chamber 27 to overcome the pressure of the fluid in the 85 motor chamber on piston 20 and thus cause the pressure of the incoming fluid against the piston 22 to move the valve downwardly. To this end I may provide a pilot valve 90 comprising a valve stem 40 slidably mounted in a sleeve 41 provided in an extension 42 of the casing 15. Three sets of passages are provided within this extension 42, one an inlet passage 43 communicating through a 95 port 44 with the interior of the casing sleeve 100 between pistons 20 and 22. The second passage 45 communicates with the cylinder space 27 as illustrated; and the third passage 47 communicates through a pipe 48, shown in dotted lines, with the outlet port 105 17.

The stem 40 has a reduced central portion 50 of such length and size relative to the locations of the openings 51, 52 and 53 within the sleeve which communicate respectively with the inlet port, the piston cylinder and the outlet port that it may connect passage 45 with either passage 43 or 47 but not both at the same time. The upper and lower ends 54 and 55 of the stem have a sliding fit within the sleeve and are of such dimensions that when the stem is in the central position shown in the drawing, no water can flow into or out of the cylinder space 27. By moving the stem 40 downwardly 110 communication is effected from the port 16 through passage 43, the concentric space surrounding the reduced stem 50 and passage 45, to the space 27 thereby admitting water under pressure to the upper side of the piston 22. Since the upward back pressure on valve 20 from the cylinder 11 is then less than the downward pressure on the upward side of this valve piston, the net result is a downward movement of the piston 115 valve 20 and the admission of water to the cylinder 11. Upon moving the stem 40 in an opposite direction and connecting passage 45 with the passage 47 and outlet pipe 120 48, the inlet pressure on the piston set 20 125 130

and 22 being balanced the upward movement of the stem 24 can be caused only by the back pressure within the cylinder 11.

In order to utilize the motor back pressure for this purpose, I make the pistons 20 and 30 of unequal size and preferably make the effective area of piston 30 substantially one-half that of piston 20. As a result the back pressure from the cylinder 11 always tends to move the piston valve sets upwardly and this is overcome only when suitable pressure is maintained on the upper side of piston 22. When such downward pressure on piston 22 is removed by connecting passage 45 with the outlet port and the pressure of the inlet water on pistons 20 and 22 is balanced, then the upward pressure on the under side of piston valve 20 of the unbalanced piston valve set 20, 30 results in an upward movement of the valves and a consequent closing of the inlet port or opening of the port 36 to the exit 17.

It will therefore be seen that if water is flowing from the entrance 16 into the cylinder 11 the operator cannot reverse the pilot valve and stop the flow of water so suddenly as to cause the plunger to leave the water in its cylinder. Any tendency for the plunger to leave the water results in a decreased pressure within the cylinder which either slows up movement of the piston valve or is insufficient to move the piston valve at all. Hence the flow of incoming water cannot be stopped instantly and its retardation rate is controlled by the inertia of the moving plunger 10 and its load 13. As this rate of movement gradually decreases the unbalanced weight of the load thus gradually exerts more and more pressure upon the valve piston 20 until finally the valve piston 20 is moved upwardly to close the valve completely.

Similarly the downward movement of the plunger cannot be stopped so quickly as to cause a shock but is automatically controlled by the mechanism as arranged. When the piston sets are in their uppermost position and the load is moving rapidly downwardly and the water has free exit through port 17, any attempt on the part of the operator to close the outlet valve by admitting water to the cylinder casing 27 results in producing back pressure on the under side of valve piston 20 which neutralizes either completely or partially the downward pressure on the upper side of valve 22, thereby preventing rapid downward movement of the valve sets and too sudden a closure of the exit. The valve sets will therefore stop in their downward movement or move as slowly as required until the back pressure in cylinder 11 is decreased to a sufficient extent to permit the valve 30 to be closed.

In order to control the device manually,

I may employ linkage connections which are substantially the same as those shown in the prior patent to Reynolds. As illustrated, a lever 56 which is adapted to be moved by the operator is pivotally mounted on a lug 57 projecting from the wall 26. A linkage connection between the stem 40 and the rod 25 is provided through a lever 58 pivotally connected at one end to the rod 25 and at the other end to a link 59 which is pivotally mounted on the upper end of the stem 40. The levers 56 and 58 are connected by a link 60.

It will therefore be seen that with such a construction when lever 56 is moved downwardly by the operator the pivotal connection 61 between lever 58 and rod 25 first serves as a fulcrum whereby movement of the link 60 causes the link 59 and the stem 40 to descend, thus permitting water to flow into the cylinder space 27. The outer end of the lever 56 is held in its new position, hence the pivotal point 62 is temporarily fixed. Consequently as soon as water begins to flow and move the piston valve sets downwardly, the pivotal point 61 now descends and turns lever 58 on its new fulcrum 62, thus serving to lift the stem 40 and thereby return it to a neutral position. As a result, further downward movement of the valve sets is prevented. When lever 56 is raised to its uppermost position the reverse action takes place and the linkages first move the stem 40 upwardly and then as the valve sets change their positions return the pilot valve to its neutral closed position.

It will now be obvious that this construction is equally applicable to motors containing a piston or ram located for horizontal reciprocating movement and to various other hydraulic devices, provided there is back pressure capable of actuating the valve pistons as above described. It might also be observed that in the simplified construction illustrated, the main valve piston 20 serves in a double capacity as a part common to two sets of piston valves, one of which is balanced under the pressure of the incoming water and the other of which is a differential set so arranged that the inlet valve may be closed and the outlet valve opened by the back pressure of the water in the hydraulic motor being operated. The member 22 serves both to balance the pressure of the inlet fluid on valve 20 and as a piston in the valve operating cylinder 27, whereby when fluid is admitted to cylinder 27 the inlet fluid pressure may close the outlet port and open the inlet to the motor. Upon moving the pilot valve to release the pressure in the operating cylinder the back pressure on valve 20 from the motor moves the piston 22 in the reverse direction, hence the operating cylinder-piston device 27-22 has a direct action only in one direction. The motor

back pressure is the sole motive power acting in the opposite direction to close the inlet and open the outlet ports. It is clear that other arrangements of the pistons and valves may be employed within the scope of the objects of my invention and the appended claims, it being merely essential that the parts be so arranged that the motor back pressure may close the inlet valve and open the outlet valve when permitted by fluid movement in the operating cylinder 27. It also is to be observed that in actual practice the balancing piston may be made slightly larger than valve 20 to overcome friction, but the expressions "balanced pistons" and the like as used in the description and claims are to be interpreted as fully covering such a construction. The expression "differential pistons" is likewise to be construed broadly. Moreover, it is immaterial, within the scope of my invention, which of the two relatively movable members, constituting piston and cylinder is actually movable and that equivalent arrangements well known in this art may be employed.

Having thus described my invention, what I claim as new and desire to secure by Letters Patent is:—

1. In combination with a hydraulic motor, a three way valve comprising a casing having an inlet port, an outlet port and a port to the motor and a piston valve device so constructed and arranged relative to said ports that the back pressure from the motor is the sole motive power to effect closing movement of the inlet valve.

2. A hydraulic valve for a motor comprising a casing having inlet, outlet and motor ports, a set of piston valves therein controlling the flow of water to and from the motor and means to move the valves to connect the inlet with the motor port, said parts being constructed and arranged so that the hydraulic pressure in said motor controls the rate of movement of the piston valves.

3. A hydraulic valve comprising a casing having inlet, outlet and motor ports, a device to control the flow of water through said motor port having differential piston valves so arranged between the motor port and the other ports that the hydraulic pressure in the motor port automatically regulates the rate of the valve movement, and means including a pilot valve to move said device to open the connection from the inlet to the motor port.

4. A hydraulic valve for a motor comprising a casing having inlet, outlet and motor ports and means including a set of piston valves therein controlling the flow of water to and from the motor whereby the inlet fluid pressure is utilized to move the pistons against the motor pressure for closing the outlet valve and opening the inlet valve and the motor back pressure is used to close the inlet and open the outlet

valves at a rate depending upon the back pressure in the motor.

5. A hydraulic valve comprising a casing having inlet, outlet and motor ports, a piston valve controlling the flow of water from the inlet to the motor port, a piston connected with said valve and arranged to balance the inlet pressure thereon and a valve between the motor and outlet ports, said ports being so arranged that the motor back pressure is the sole motive power to close the inlet port and open the outlet port.

6. A hydraulic valve for a motor comprising a casing having inlet, outlet and motor ports, pistons balanced against the inlet pressure and forming an inlet valve, an outlet valve cooperating with said pistons, said parts being so arranged that the motor back pressure may close the inlet valve and open the outlet valve, and means to open the inlet valve against such back pressure.

7. A hydraulic valve comprising a casing having an inlet port, an outlet port and a motor port and a piston valve device having balanced pistons on opposite sides of the inlet port and unbalanced pistons between the motor port and the other ports, whereby the hydraulic pressure in the motor port may control the rate of movement of said device.

8. In combination with a hydraulic motor, a valve mechanism therefor comprising a casing having inlet, outlet and motor ports, a balanced piston valve set receiving the fluid pressure from the inlet port and a differential piston valve set receiving the back pressure of the fluid from the motor, a valve common to said sets controlling the flow of fluid from the inlet to the motor port, said parts being constructed and arranged to prevent too sudden changes in the rate of fluid movement.

9. A hydraulic valve comprising a valve casing having inlet, outlet and motor ports, a main valve controlling the flow of fluid under pressure from the inlet to the motor port, a second valve controlling the exit of fluid from the motor port and means combined therewith operable by direct fluid pressure to open the main valve and to permit back pressure from the motor to close said main valve and to open the outlet valve.

10. A hydraulic valve comprising a casing having inlet, outlet and motor ports, a valve piston between the inlet and motor ports, a valve piston between the motor and outlet ports and a piston connected with said valve pistons operable by fluid pressure to open the valve between the inlet and motor ports, said piston and inlet valve piston being in balanced relation and the valve pistons being constructed and arranged relative to the

casing and said ports so as to serve as a differential piston operable by back pressure from the motor to close the inlet valve gradually and prevent shock.

- 5 11. A hydraulic valve comprising a casing closed at one end which has inlet, outlet and motor ports, a piston adjacent said closed end, a pilot valve to admit fluid under pressure to said closed end and move 55 the piston in one direction and unbalanced piston valves between the motor port and the other ports connected with said piston, said parts being so arranged that the inlet valve is opened by the piston and closed 60 by the back pressure in the motor port at a rate controlled by pressure in said motor port.

- 10 12. A hydraulic valve comprising a casing closed at one end and having inlet, outlet and motor ports spaced longitudinally thereof, a piston valve between the inlet and motor ports, a piston adjacent said closed end and constructed to balance said valve against the inlet pressure, means including 65 a relatively movable piston and cylinder forming an outlet valve and cooperating with said piston valve to cause a differential pressure to be exerted thereon from the motor port which tends to close the inlet 70 port, and means including a pilot valve arranged to admit fluid pressure to the casing to move said piston and open the inlet port.

- 15 13. A hydraulic valve comprising a cylinder casing having inlet, motor and outlet ports, a main piston valve between the inlet and motor ports adapted to limit the flow of water therebetween, a piston valve of smaller effective area between the motor and outlet ports to control the outflow of water, a piston connected to said valves arranged 75 to balance the pressure of the inflowing water on the main valve and means including a pilot valve effective to unbalance said piston and valve and cause the main valve to open at a rate controlled by the back pressure of the water in said motor port.

- 20 14. A hydraulic valve comprising a cylindrical casing having inlet, outlet and motor ports spaced longitudinally of the

casing, a piston valve between the inlet and motor ports, a piston connected to said valve and arranged to balance the same against the inlet pressure means including 55 a member adjacent the outlet port which cooperates with said piston valve to form a differential piston set, whereby the motor back pressure tends to move the same and close the inlet port, and means including an operating piston cylinder and a pilot 60 valve to move the piston against the motor pressure and open the inlet and close the outlet valves.

15 15. A hydraulic valve comprising a cylindrical casing having inlet and motor ports opening therefrom and a reduced end portion provided with an outlet port, a main piston valve between said inlet and motor ports, a piston on the opposite side of the inlet port to balance said valve, an 65 outlet valve of smaller effective area than said main valve located between the motor port and the outlet port, means connecting said piston and valves for simultaneous 70 sliding movement, and means including a pilot valve to move said piston and open the inlet valve and to permit it to close under the back pressure in the motor port.

20 16. A hydraulic valve comprising a casing which is closed at one end and has at 80 the opposite end an open reduced portion forming an outlet port, said casing being provided with an inlet port at one side and a motor port between the inlet and outlet ports, a piston between the inlet and 85 the closed end of the casing, a piston valve between the inlet and motor ports which has the same effective area as said piston and is normally balanced thereby, a smaller piston valve between the motor and outlet ports 90 connected to said main piston valve and forming an unbalanced piston set controlled by the fluid pressure in the motor port and a pilot valve arranged to introduce fluid under pressure between said piston and the 95 closed end of the casing.

Signed at Worcester, Massachusetts, this fifth day of March 1923.

THURE LARSSON,
